IGNITION FLARE

Harold W. Bixby, Encino, Calif., assignor to the United States of America as represented by the Secretary of the Navy

Application June 30, 1952, Serial No. 296,334

11 Claims. (Cl. 102—49)

This invention relates generally to aerial missiles of the ramjet type, and more particularly it pertains to a flare holder assemblage or flare holder means for holding a composition that burns actively even in the absence of an external supply of air or oxygen, and which serves to maintain combustion of the air-fuel mixture of the ramjet missile or the like, by acting as a "pilot."

It is one of the objects of this invention to provide a flare holder assemblage which will stabilize combustion in a high velocity airstream of an operating missile of the ramjet type.

Another object of the invention is to provide a flare holder assemblage for holding such flare in an aerial missile of the ramjet or similar jet-propelled device.

Even another object of this invention is to provide a generally cylindrical container to receive and hold a flare cartridge in proper operating position in order to maintain the ignition of the ramjet of the aerial missile, with the container being of suitable size and shape to fit within the body of the aerial missile, and also having supports of proper configuration to minimize the aero-dynamic drag effects, while maintaining proper operation of the ramjet.

It is still even another object of this invention to provide a flare holder assemblage for stabilizing combustion of a supersonic airstream by making maximum use of the back pressure in the ramjet.

Still another object of this invention is to provide a flare holder assemblage which is economical to manufacture, easy to install in a ramjet missile and reliable and efficient in operation.

Other objects and many of the attendant advantages of this invention will be readily appreciated as the same becomes better understood by reference to the following detailed description when considered in connection with the accompanying drawings, and in which:

Fig. 1 is an axial section taken through an aerial missile of the ramjet type, showing the flare holder assemblage mounted in position and embodying the features of the invention;

Fig. 2 is a cross section on the line 2—2 of Fig. 1; and

Fig. 3 is a cross section on the line 3—3 of Fig. 1.

In accordance with the invention, an aerial missile of the ramjet type or the like is provided with a flare holder assemblage or means for holding an ignition flare therein. This assemblage comprises a cylindrical body portion having a cylindrical bore to receive a flare. A plurality of threaded holes are provided near the forward end of the bore to receive cone-point set screws whose sharp-pointed inner ends are adapted to enter the pasteboard flare case to hold the flare firmly in operating position. A frustoconical rear section, small enough at its rear end to fit within the ramjet missile, is secured to the cylindrical body member of the assemblage by a plurality of radially arranged struts having rounded front edges inclined at an angle, and wedge-shaped rear portions to present a streamlined contour. At the front or forward end of the cylinder, within the body, there is secured a

fitting which has a threaded, reduced forward end adapted to receive an internally threaded ring, which, when screwed into position, provides a continuation of the outer surface of the main cylindrical body. A plug, 5 having a rounded forward end and a threaded, reduced rearward extension, is adapted to enter the threaded ring, which, when fully engaged, forms an outer surface continuation of that of the ring. In addition to the above, radial struts are secured to the outer surface of the ring, 10 and are surrounded at their outer ends by a ring which is adapted to be clamped firmly between the forward section of the ramjet missile and the tail pipe section of the ramjet missile, thereby supporting the holder with its flare within the tail pipe section of the ramjet missile.

Referring now to the drawings, there is shown in Fig. 1, a portion of the outer skin 15 of an aerial missile 16 of the ramjet type. Missile 16 has a forward section 17 including a diffuser (not shown), and a tailpipe section 18 which are supported by bulkheads or strut members (not shown) within the missile.

A flare holder assemblage or flare holder means 19 comprising the invention, is mounted between forward section 17 and tailpipe section 18. The body of the flare holder assemblage 19 comprises a substantially cylindrical member 20 having a cylindrical bore 21 of proper length and diameter to receive a flare 22 (shown in phantom lines). This body member 20 may be made of any suitable material, such as steel, Duralumin and the like, and, of course, its wall thickness will vary slightly with the material used.

A plurality of threaded holes 23 are provided in member 20 near the front or forward end 24 thereof. These threaded holes 23 receive cone-point socket-head set screws 34 such as those of the Allen type. It will be understood that the flare 22 has a covering of pasteboard 35 or similar material, and when it is inserted in the bore 21, the set screws 34 are screwed down so that their sharp-pointed inner ends 36 will enter this pasteboard flare case 35 and hold the flare 22 firmly in position.

A frusto-conical rear section 38 is provided, which is small enough at its rear end 39 to fit within the tailpipe section 18. Section 38 may be flared an inch or so in inside diameter from front to rear, and may be about four inches, more or less, in length, when used in a six inch ramjet missile, although it is to be understood that the actual dimensions may be varied widely, to suit specific cases.

This frusto-conical rear section 38 is secured to the cylindrical body member 20 by a suitable number of 50 radially arranged struts 40, four being indicated here. These struts 40 have rounded front edges 47, inclined at a suitable angle as shown, and wedge-shaped rear portions 48, so that their horizontal contours may be broadly described as "streamlined." It will be noted that the 55 struts 40 are secured to the body member 20 by welds 49 and to the rear section 38 by other welds 50, the interior of the rear section 38 being completely unobstructed and smooth.

At the forward end 24 of member 20, there is provided 60 a fitting 51 which is shaped as shown, and is secured within member 20 by welds at 52. For lightness, fitting 52 may be hollow. Its reduced forward end 53 has threads 54 thereon, fitting in the correspondingly threaded ring 55, which, when in position, will provide a continuation of the outer surface 56 of member 20 as shown in Fig. 1.

A plug 57, having a rounded forward end 58, and hollowed as shown at 59, also has a reduced rearward extension 60 threaded at 61 to enter the ring 55. When fully engaged, the outer surface 62 of plug 57 will form a continuation of that of ring 55.

Radial struts 63 are secured to the outer surface 64 of

ring 55, as by welds 66. These struts 63 preferably are equal in number to the struts 40 and are in line with the latter in order to minimize the aerodynamic drag. Struts 63 should preferably have rounded front edges 67 and wedge-shaped trailing ends 68, like the struts 40.

A ring 74 surrounds the outer ends of struts 63, the struts being secured to the ring by welds 75 as shown in Fig. 1. It will be noted that all the struts, of both sets, are of such lengths that they will just fit in the tailpipe 18 of the ramjet missile, here assumed to be 6 inches.

There is a difference, however, in how the struts 63 and 40 are mounted in the missile. Struts 63 are held firmly by the ring 74, which is clamped between the forward section 17 of the ramjet missile 16 and the tailpipe section 18, and thus are rigid with the ramjet, while struts 40 merely abut against the inner surface of the tailpipe section 17, and thus hold the rear section 38 centered. This makes it possible for the assembly to expand and contract independently of the ramjet missile 16, thereby preventing strain and warping of any of the parts, under the intense heat of combustion.

It has been found that slight changes in the relative shapes and dimensions of various parts of the assemblage 19 have pronounced effects on the operation of the ramjet missile 16, so that flare holding assemblage 19 which is found best for one specific fuel is not necessarily best also for another fuel mixture. For example, while heptane and kerosene may be burned efficiently with the same type of flare holder assemblage, changes are necessary if propylene oxide is to be used as fuel. However, the general structure and proportions will not deviate unduly from the design illustrated, which may be considered a diagrammatic disclosure of an average type.

Having described the invention, its operation will now be briefly described.

An aerial missile 16 of the ramjet type or the like is launched from a launching platform by means of a booster rocket (not shown). After the booster rocket has spent its power, it separates from aerial missile 16 and drops to the earth, with missile 16 continuing along its trajectory after the combustion system of the ramjet has been set into operation. This is achieved by the flare 22 being ignited in any suitable manner, such as by remote control. The flame from the burning of the composition of flare 22 extends rearwardly through the rear section 38 of the flare holder assembly and ignites the air-fuel mixture which is, in the meantime, flowing through the ramjet, and maintains the air-fuel mixture in an ignited condition throughout the course of flight of missile 16.

Obviously many modifications and variations of the present invention are possible in light of the above teachings. It is, therefore, to be understood that within the scope of the appended claims the invention may be practiced otherwise than as specifically described.

What is claimed is:

1. In combination with an aerial missile of the ramjet type having a forward diffuser section and a tailpipe section, a flare holder assemblage for holding an ignition flare in the combustion chamber of said tailpipe section, comprising, a body having a portion thereof with a bore for receiving said flare, means for holding said flare in position in said bore, means secured to the rear portion of said body for freely supporting said body against said tailpipe, means located between said diffuser and tailpipe sections, and means secured to the forward portion of said body and to said last mentioned means for rigidly supporting said body, thereby making it possible for said assemblage to expand and contract independently of said aerial missile and thus preventing straining and warpage of parts under the intense heat during combustion of the air-fuel mixture.

2. In combination with an aerial missile of the ramjet type having a forward diffuser section and a tailpipe section, a flare holder assemblage for holding an ignition flare in the combustion chamber of said tailpipe section,

comprising, a streamlined body having a portion thereof with a bore for receiving said flare, means for holding said flare in position in said bore, means secured to the rear portion of said body for freely supporting said body against said tailpipe, means cooperating with rear supporting means for shielding the flame from said flare during combustion, means including a ring located between said diffuser and tailpipe sections, and means secured to the forward portion of said body and to said ring for rigidly supporting said body, thereby making it possible for said assemblage to expand and contract independently of said aerial missile and thus preventing straining and warpage of parts under the intense heat during combustion of the air-fuel mixture in said combustion chamber.

3. In combination with an aerial missile of the ramjet type having a forward diffuser section and a tailpipe section, a flare holder assemblage for holding an ignition flare in the combustion chamber of said tailpipe section, comprising, a streamlined body having a portion thereof with a bore for receiving said flare, means for holding said flare in position in said bore, strut means secured to the rear portion of said body for freely supporting said body against said tailpipe, means cooperating with said rear strut means for shielding the flame from said flare during combustion, a ring secured between said diffuser section and said tailpipe section, and strut means secured to the forward portion of said body and to said ring for rigidly supporting said body, thereby making it possible for said assemblage to expand and contract independently of said aerial missile and thus preventing straining and warpage of parts under the intense heat during combustion of the air-fuel mixture.

4. An arrangement as set forth in claim 3, wherein said strut means at the forward and rear portions of said body comprise a plurality of radially arranged struts having rounded forward edges and wedge-shaped rear portions.

5. An arrangement as set forth in claim 3, wherein said means cooperating with said rear strut means comprises a hollow frusto-conical member having its forward, small end secured to said rear strut means and in axial alignment with said body.

6. A flare holder assemblage for holding an ignition flare in an aerial missile of the ramjet type having a forward section with a diffuser located therein and a tailpipe section, comprising, a body having a portion thereof with a bore for receiving said flare, means for holding said flare in position in said bore, means secured to the rear portion of said body for freely supporting said body against said tailpipe section, means located between said diffuser and tailpipe sections, and means secured to the forward portion of said body and to said last mentioned means for rigidly supporting said body, thereby making it possible for said assemblage to expand and contract independently of said aerial missile and thus preventing straining and warpage of parts under the intense heat during combustion of the air-fuel mixture.

7. A flare holder assemblage for holding an ignition flare in an aerial missile of the ramjet type having a forward section with a diffuser located therein and a tailpipe section, comprising, a streamlined body having a portion thereof with a bore for receiving said flare, means for holding said flare in position in said bore, streamlined means secured to the rear portion of said body for freely supporting said body against said tailpipe, means including a ring located between said diffuser and tailpipe section, and streamlined means secured to the forward portion of said body and to said ring for rigidly supporting said body, thereby making it possible for said assemblage to expand and contract independently of said aerial missile and thus preventing straining and warpage of parts under the intense heat during combustion of the air-fuel mixture.

8. An arrangement as set forth in claim 7, wherein said rear and forward streamlined means comprise a plurality

of radially arranged strut members having rounded forward edges and wedge-shaped rear portions.

9. An arrangement as set forth in claim 8, and shielding means secured to said rear streamlined means for shielding the flame from said flare during combustion.

10. In combination with an aerial missile of the ramjet type having a diffuser section and a tailpipe section, a flare holder assemblage for holding an ignition flare in the combustion chamber of said tailpipe section, comprising, a streamlined body having a portion thereof with a bore for receiving said flare, means secured to the rear portion of said body for freely supporting said body against said tailpipe section, and means secured to the forward portion of said body and including an annular ring located between said diffuser section and said tailpipe section for rigidly supporting said body, thereby making it possible for said assemblage to expand and contract independently of said aerial missile and thus preventing straining and warpage of parts under the intense heat generated during combustion of the air-fuel mixture in said combustion chamber.

11. A flare holder assemblage for holding an ignition flare in an aerial missile of the ramjet type having a forward section and a tailpipe section, comprising, a streamline body having a portion thereof with a bore for receiving said flare, means for holding said flare in position in said bore, a first plurality of radially arranged strut

members having rounded forward edges and wedge-shaped rear portions secured to the rear portion of said body for freely supporting said body against said tailpipe section, a second plurality of radially arranged strut members having rounded forward edges and wedge-shaped rear portions secured to the forward portion of said body and also between said forward and tailpipe sections for rigidly supporting said body, and shielding means secured to said first plurality of radially arranged strut members for shielding the flame from said flare during combustion, said shielding means including a hollow frusto-conical member having its forward, reduced end secured to said first plurality of radially arranged strut members and in axial alignment with said body, whereby it is possible for said assemblage to expand and contract individually of said aerial missile and thus prevent straining and warpage of parts under the intense heat generated during the combustion of the air-fuel mixture.
